UNITED STATES PATENT OFFICE.

HALVER R. STRAIGHT, OF ADEL, IOWA.

GROOVED-END HOLLOW BUILDING TILE.

1,411,532.

Specification of Letters Patent.

Patented Apr. 4, 1922.

Application filed October 14, 1918. Serial No. 258,076.

To all whom it may concern:

Be it known that I, HALVER R. STRAIGHT, a citizen of the United States, and a resident of Adel, in the county of Dallas and State of Iowa, have invented a certain new and useful Grooved-End Hollow Building Tile, of which the following is a specification.

The object of my invention is to provide a building tile of the ordinary hollow type having the ends formed with grooves which are preferably arranged parallel with the face of the wall in which the building tile is mounted, the grooves being relatively small, whereby it is made possible to produce a masonry structure having a bond of maximum efficiency at the mortar joints, and whereby the mortar is properly held during the "pointing" up of the joints.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Figure 1 shows a perspective view of a hollow tile building block embodying my invention; and

Figure 2 shows a top or plan view of two of the blocks laid together in a course.

In the accompanying drawings I have used the reference numeral 10 to indicate generally the front wall or face of a hollow tile building block having the top wall or face 11, the rear wall or face 12 and the bottom wall 13. The tile is hollow and has a central vertical partition 14. The tile may be of various sizes and shapes but for illustration may be five inches high, eight inches wide, and twelve inches long, outside dimensions, with front and rear walls one inch thick, top and bottom walls three-fourths inch thick, and partitions five-eighths inch thick.

The end faces of the surfaces of the tile are provided with grooves 16 which are preferably arranged parallel with the outer face of the tile wall 10, as illustrated in Figure 1.

These grooves are quite small and may be arranged at various different angles, but should not be at right-angles to the face of a wall, and I believe the best results are secured when the grooves are parallel with the face of the wall.

The grooves are in the end only of the tile. In Figure 2 I have illustrated a portion of a wall in which two of my improved tile are arranged end to end in a masonry course with a layer of mortar 17 between them.

The advantages of these grooved end tile are very important.

When the one tile is laid up adjacent to another in the course, the mortar is not held between two smooth surfaces, but is pressed into the grooves, and it is obvious that the mortar will be held in the joint better than would be the case where the end surfaces were smooth, because the mortar in flowing out between the ends, as the ends are pressed together during the laying up process, will flow into the grooves and form ridges of mortar of substantially the same shape as the grooves.

Naturally the tendency of the mortar to flow out at the sides of the wall is reduced when the mortar enters the grooves, because the ridges of mortar thus formed, prevent the floating of the mortar outward over the tile ends on the film of moisture, which forms between the mortar and the tile end, which floating occurs with a smooth end tile.

It thus follows that the mortar between the ends of the adjacent tile will endure a greater pressure without being floated or forced laterally from between the tile, and hence greater pressure can be used in placing the tile adjacent to each other, and greater density in the mortar joint will be secured, which results in the forming of a better bond between the mortar and tile than can be secured with smooth end tile.

With grooves in the ends of the tile, the mortar fills the grooves almost immediately upon touching. At the same time there is a film of moisture collected almost immediately between the mortar and the end of the tile. If the tile is at all hard, this film of moisture lays between the surface of the mortar and the end of the tile and the friction of the mortar across the end of a smooth tile is less than the friction of the mortar across the end of my grooved tile, together with the internal friction of the mortar over the mortar that has gone into the groove.

It is better to have a comparatively large number of grooves of slight depth than to have fewer grooves of greater depth, for the reason that even with shallow grooves

the mortar may not in all instances penetrate clear to the bottom of the grooves, and with grooves of greater depth the mortar would not entirely fill the grooves, and 5 for that reason a poorer mortar joint would be secured.

Mortar that has been hard pressed between the ends of the tile, unites with a 10 most perfect adhesion onto the tile. At least the adhesion is more perfect according to the pressure because of the better contact and more air pressed out. When 15 this mortar finally sets it is more perfectly bonded and is less liable to present weathering crevices than if pressed to any degree less hard.

Therefore, mortar joints that are firmly bonded together between the ends of the tile, weather from the outside surface only, 20 while if not perfectly bonded and if the joint is in the least loose between the ends, another surface is presented to the weathering action of the elements.

Where the ends of the tile are smooth it 25 is obvious that during the "pointing" up of the joint when a trowel is run along the mortar joint at the surface of the wall, there is a pressure inwardly on the mortar which sometimes results in breaking the 30 adhesion between the mortar and the tile while the mortar is green.

The adhesion once loosened can never be entirely properly restored and when the 35 adhesion has been so loosened no proper bond is ever secured and a water proof joint does not result.

With my grooved end tile the pressure of the trowel in "pointing" up the joint will not 40 loosen the joint because it is necessary to shear the ridges above mentioned from the other portion of the mortar, and this I have found will not be done by the pressure of the trowel during the "pointing" up.

Even if the tile is soft burned, the grooves 45 still have great advantages, because the film of moisture formed is absorbed by the tile, and this destroys the possibility of the best bond, because moisture required by the mortar for crystallization of cement and 50 lime has been taken away by the tile, and the mortar is dried out rather than crystallized thoroughly. Obviously mortar not thoroughly crystallized will be held more firmly in place between the grooved surfaces, than between smooth end tile, especially 55 because the mortar in crystallizing expands slightly and aids in creating a bet-

ter bond between grooved end tile, than between smooth end tile.

Thus while the best bond can be secured 60 with vitrified tile, my grooved end tile will provide a better mortar joint and the mortar will more properly "set" and will better remain in position with my tile than would be the case where the ends are 65 smooth, and as a result a mortar joint of maximum efficiency is secured, and the possibility of moisture getting through the mortar joint is very greatly reduced.

Where the mortar properly "sets" at the 70 proper time, and properly bonds with the tile it is hard like stone and is not much subject to action of the weather.

Where mortar is not properly "set" or does not properly bond it will be seen that 75 it will be much more likely to chip off or break off owing to the action of the weather, or any shocks that the wall may sustain.

It will be seen from the foregoing that instead of inclined vertical grooves, a great 80 many forms of depressions in the end wall of the tile might be employed which would serve to receive mortar for forming ribs or their equivalents for making a mortar joint which would have very largely the ad- 85 vantages hereinbefore mentioned.

I claim as my invention:

1. A hollow tile block for wall building purposes, having at each end two upright side members and two horizontally arranged connecting members, all of said members being formed with grooves, whereby mortar placed between two adjacent blocks may be compressed by moving the blocks towards each other and the mortar 95 forced into said grooves to thereby lock the mortar in position by said grooves, and whereby the mortar between the side members is held in place by being united to the mortar between the horizontal mem- 100 bers.

2. A hollow building tile comprising a front wall, a back wall, and top and bottom walls connecting the said walls, the ends of the top and bottom walls lying in the same 105 planes as the ends of the front and back walls, the ends of each of said walls being provided with relatively small shallow grooves designed to receive mortar placed between adjacent tiles so as to form an 110 endless keyed bond at each end of the tile.

Des Moines, Iowa, October 9, 1918.

HALVER R. STRAIGHT.
